UNITED STATES PATENT OFFICE.

KRAFT BOOTH, OF PHILADELPHIA, PENNSYLVANIA, ASSIGNOR TO GILLINDER & SONS, INC., A CORPORATION OF PENNSYLVANIA.

DESIGN FOR A GLASS GLOBE FOR LIGHTS.

44,722.

Specification for Design.

Patented Oct. 14, 1913.

Application filed August 8, 1913. Serial No. 783,822. Term of patent 7 years.

To all whom it may concern:

Be it known that I, KRAFT BOOTH, a citizen of the United States, residing in the city and county of Philadelphia, State of Pennsylvania, have invented a new, original, and ornamental Design for a Glass Globe for a Light, of which the following is a specification, reference being had to the accompanying drawing, forming part thereof.

The figure is a side elevation of a glass globe for a light, showing my new design.

I claim:

The ornamental design for a glass globe for a light, as shown.

KRAFT BOOTH.
